Fig. 4

FIGURE 1 is a top perspective view of a closure for a container, showing my new design where approximately one-third of the depending flange is unscalloped opposite the lift tab;

FIGURE 2 is a side elevational view of the closure of FIGURE 1, the side not shown being the same as the side shown;

FIGURE 3 is a rear elevational view of the closure of FIGURE 1; and

FIG. 4 is a rear elevational view of another embodiment of a closure for a container, showing my new design wherein the depending flange is scalloped all the way around except in the area of the lift tab.

I claim:

The ornamental designs for a closure for a container, substantially as shown and described.
